UNITED STATES PATENT OFFICE

1,985,914

AUTOMATIC VOLUME CONTROL CIRCUITS

Wendell L. Carlson, Haddonfield, N. J., assignor
to General Electric Company, a corporation of
New York

Application August 29, 1930, Serial No. 478,686

2 Claims. (Cl. 250—20)

The present invention relates to radio receiving apparatus embodying hot-cathode, grid-controlled electric discharge devices commonly known as vacuum tubes, arranged to amplify and detect electric signals, such as modulated radio waves, and has for its object to provide an improved circuit arrangement in connection with an amplifier and detector in such apparatus, whereby it may operate automatically to deliver substantially a constant signal output in response to a signal input of varying strength.

In accordance with the invention, advantage is taken of the fact that the response or amplification characteristic of an electric discharge amplifier may be varied between wide limits by slight changes in the biasing potential applied to the control electrode or grid circuit thereof when operating such circuit in the positive range of biasing potentials, and of the fact as is well known, that the anode current of a detector arranged for bias or anode circuit detection, increases with increases in the strength of an applied signal.

Further in accordance with the invention, a biasing circuit common to the output or anode circuit of the detector and the input or grid circuit of the amplifier is so arranged that the apparatus is highly sensitive to variations in the strength of the signals applied to the detector to provide a more uniform output from the amplifier, the amplifier bias being automatically increased in a positive direction with increased signal strength applied to the detector.

The invention will however be better understood from the following description when considered in connection with the accompanying drawing, and its scope will be pointed out in the appended claims:

In the drawing, Fig. 1 is a schematic wiring diagram of an electric signal amplifier and detector which may form a part of radio receiving apparatus and the like, provided with an automatic volume control circuit embodying the invention, and Fig. 2 is a curve diagram illustrating an operating characteristic of the apparatus of Fig. 1.

Referring to Fig. 1 of the drawing, 5 is an electric discharge device of the hot-cathode, three-element type representing any suitable device of this character for operation as a bias detector of radio signals or modulated waves. The detector is provided with an input or grid circuit 6, an output or anode circuit 7, and a cathode return lead 8 common to both the grid and anode circuits. Suitable anode and grid bias potentials

for the operation of device 5 as a bias detector are provided by a source of direct current operating potentials represented by a voltage supply resistor 9, having positive and negative supply terminals 10—10 as indicated, to which resistor the grid and anode circuits 6 and 7, and the cathode return lead 8 are connected at suitable tap points as indicated at 11, 12 and 13 respectively.

As will readily be understood, the above described connections are such that with a desired positive potential applied to the anode circuit 7 with respect to the cathode, the grid circuit 6 is provided with a negative potential with respect to the cathode such that the anode current is reduced substantially to zero, with no modulated signal or carrier wave on the grid or input circuit; this being as is well known, a condition for proper operation of device 5 as a bias detector. Upon the application of signal voltage to the input or grid circuit through a suitable input device such as a high frequency transformer 15, the anode current will increase in response to increases in the strength of the carrier wave. Modulated signals received by the detector, are transmitted to output terminals 16 from the anode circuit through an output device such as a low or audio frequency transformer 17.

Amplified signal voltage is applied to the detector 5 thru a suitable vacuum tube or electric discharge amplifier having signal input terminals 18, and an output circuit 19 connected with the detector input or coupling device 15. The amplifier may include any desired number of stages. In the present example, for the sake of simplicity and clearness but one stage is shown and includes an electric discharge amplifier device 20 of the type employed as a detector at 5, and a coupling or input device 21 interposed between the input terminals 18 and an input or control electrode circuit 22 for device 20. The anode or output circuit of device 20 is provided by the output circuit 19 of the amplifier, to which suitable operating potential is applied through connections with the potential supply resistor 9 at a tap point 14 and through a cathode return lead 23 for the amplifier connected with the resistor 9 at a variable tap point 24.

Bias potential for the amplifier grid or control electrode is supplied thereto through a lead 25 connected with an impedance such as a resistor 26 in the output circuit of the detector 5, to derive a variable bias potential therefrom responsive to changes in the signal output. The value of the potential applied to the control electrode or bias

circuit of the amplifier through lead 25 is provided by an adjustable tap 27 on the impedance, which in the present example is arranged as indicated, to vary the voltage by varying the impedance or resistance. The bias resistor or impedance 26 is preferably located as shown in the cathode return lead 8 for the detector 5 whereby it operates to apply an additional bias to the detector in response to increased signal input.

10 By returning the control grid or input circuit of the amplifier 20 to the positive end of the bias resistor 26 a variable positive bias or control potential, having a certain fixed initial value, is applied to the control electrode circuit by the 15 detector device 5, in accordance with the signal strength. It will be seen that if the variable tap point 24 is brought to a point opposite the tap point 12, the total applied bias potential to the control grid of the amplifier device 20 will be that 20 provided by the drop in resistor 26 and will be a positive bias, instead of a negative bias as is common with amplifier devices heretofore used for signal amplification and the like.

The object of the above described arrangement 25 is to provide a means for reducing the amplification of the amplifier by causing the bias potential applied to the control electrode circuit, thereof to become increasingly more positive with increased applied signal strength, thereby correspondingly 30 reducing the amplification, to maintain the average value of amplification and the detector output substantially constant.

With the tap point 24 for the cathode return 35 lead of device 20 located substantially opposite the point 12, the detector through the medium of the resistor 26 would supply all of the bias voltage for the amplifier device 20. Should this initial bias, with no signal applied to the detector, be too high or too low, the tap point 24 may be 40 moved to a position such as that shown in the drawing, along the potential supply resistor 9 to provide the desired value of initial bias on amplifier device 20 for normal operation. In the present example, tap point 24 is located at a point 45 more positive than tap point 12 whereby the positive bias potential provided thereby is applied in opposition to the positive bias potential supplied by the bias resistor 26.

The bias potential applied to the detector 5 is 50 such that normally with an electric discharge device of the type shown, the anode current is reduced substantially to zero or to a small fraction of a milliampere as hereinbefore described. The bias potential applied to the amplifier 20 between its control grid and its cathode is then adjusted by applying a suitable potential to the cathode by moving the tap point 24 or the tap 27. In the present example and in the usual case with electric discharge devices of the type shown, the 55 tap point 24 is moved to a point more positive to balance or reduce the positive bias applied through the bias resistor 26. The bias resistor 26 thus simultaneously applies a negative bias to the detector and a positive bias to the amplifier.

60 It will be seen that with the above-described arrangement the volume setting of the amplifier depends upon the bias voltage applied thereto and may be adjusted by adjusting the resistor 26 or the tap point 24.

65 It will be seen also that the circuit arrangement is such that a positive bias potential is applied to the amplifier from resistor 26, while an additional negative bias potential is applied to the detector over that derived from the supply source 9 between tap points 11 and 12. This arrangement, in

accordance with the invention, provides for the proper operation of the negative bias detector and for the operation of the amplifier with a positive bias in the steep portion of its grid-bias amplification characteristic as indicated in Fig. 2, to which, 5 along with Fig. 1, attention is now directed.

Referring to Fig. 2, the amplification provided by an amplifier such as device 20 and associated circuits is indicated by a curve 28, 29, 30, characteristic of the amplifier tube 20. It will be seen 10 from the curve that as the amplifier grid-bias potential is increased from zero to a more negative value, the amplification falls off gradually, while as the amplifier and grid-bias voltage is increased from zero to a more positive value, the amplification falls off very rapidly. It is the purpose 15 of the above-described control arrangement to utilize this latter portion of the characteristic in the most effective positive bias control range between points whereby a rapid and effective control of the amplification is obtained.

For the above purpose, when there is no signal applied to the amplifier 20 and detector 5, the amplifier bias potential is so adjusted that the amplification is substantially at a point on the curve indicated at 29, the bias potential on the control grid of amplifier device 20 being then slightly negative. When a signal or modulated wave is applied to the input terminals 18, and through the amplifier 20, the bias potential provided by impedance 26 in the detector output or anode circuit will increase in a positive direction which will cause the amplifier 20 to operate on the steep portion of the curve such as at 30 for example. The amplifier then operates on a portion of the curve which is more sensitive to bias voltage change than the negative slope and permits a rapid reduction of signal strength when the latter tends to increase.

While but one amplifier device has been shown 40 and described in the present example, it will readily be appreciated that the same type of control may be applied to other amplifier devices connected in cascade with the single stage shown, substantially in the same manner as the connection between the amplifier device 20 and the detector 5. In any circuit arrangement, however, the amplifier bias control circuit is returned through the impedance 26 in the detector anode or output circuit whereby the impedance 26 is 45 arranged to apply a negative bias potential to the detector and a controlling positive bias to the amplifier increasingly with increasing signal strength, the amplifier being operated at such a point on the characteristic curve that an increase 50 in the bias potential causes it to operate upon that portion of its characteristic curve substantially between zero and a more positive bias voltage position, that is, on the steep slope of the positive bias portion of its grid-bias amplification 55 characteristic curve as indicated in Fig. 2.

A further advantageous feature of this volume control circuit is found in the fact that the transformer 21 of the present example, may be 60 so designed that it is sharply resonant at a desired frequency such as the intermediate frequency, in the case of a superheterodyne receiver for example, favoring selectivity at the expense of fidelity. For local reception and at such other times that strong signals are received, this circuit 65 will then be loaded heavily by the grid or control circuit of the amplifier, because of the positive bias automatically applied by the detector. This will in turn improve or restore the fidelity. This circuit arrangement is therefore readily adapted 70 to

for use in radio receiving apparatus and the like to which strong local signals are applied and operates to improve the fidelity under such conditions while for other signals it operates to in-

crease the selectivity. Stated in another way, as the bias potential on the control grid circuit of the amplifier is increased to a more positive value in response to increased signal strength, the grid circuit of the amplifier causes a heavier load upon the input device and thereby decreases the selectivity and increases the fidelity.

The control arrangement of the present example is particularly adapted for use in connection with the second detector of a superheterodyne receiver, the latter being supplied with a signal voltage through the medium of an intermediate frequency amplifier. For example, amplifier device 20 may be considered to be the last amplifier device of an intermediate frequency amplifier, and

device 5 may be considered to be the second detector in a superheterodyne receiving apparatus.

From the foregoing description, it will be seen that an amplifier and detector circuit embodying the invention provides a rapid and effective control of the output volume from the detector through the medium of a bias impedance controlling the applied grid potential to the preceding amplifier, the grid potential of the amplifier being controlled in a positive range of potentials having an amplification characteristic which is sharply sloped in a short range of positive potentials, substantially as indicated in Fig. 2, and that this arrangement permits the use of a highly

selective input device in connection with the amplifier without sacrificing the quality of the output in response to strong or local signals.

What I claim as new and desire to secure by Letters Patent of the United States, is:

1. In combination, an amplifier having an anode, a cathode, and a grid, a detector having a grid coupled to said anode of said amplifier, a cathode, and an anode, a common source of operating potential for said anodes, a resistance connected between the cathode of said detector and a point on said source negative with respect to both of said anodes, and connections from said resistance to the grid of said amplifier and from said source to the cathode of said amplifier, the potential of said resistance between said connections thereby being applied in a positive sense to the grid of said amplifier.

2. In combination, an amplifier having anode, cathode, and grid electrodes, a detector having a grid electrode coupled to said anode electrode, a cathode and an anode electrode, a common source of operating potentials for said amplifier and detector, connections from all of said electrodes to said common source of operating potentials, said connections from the grid of said amplifier and cathode of said detector to said source including a common resistance whereby the potential on said resistance produced by anode current in said detector is supplied in a positive sense to the grid of said amplifier and in a negative sense to the grid of said detector.

WENDELL L. CARLSON.
